REMOTE CONTROL APPARATUS FOR RADIO RECEIVING SETS

Henry Y. Henning, Kenmore, N. Y.

Application July 16, 1930, Serial No. 468,408

9 Claims. (Cl. 250—20)

This invention relates generally to a remote control apparatus but more particularly to an apparatus for controlling radio receiving sets from a distance.

5 One of its objects is to provide a remote control apparatus of this character having simple, reliable and effective means for operating the control devices of the receiving set, such as the tuning dial and the volume control, such means being so designed and constructed as to have the same control as if one were tuning the radio set directly by its customary control knobs.

Another object of the invention is the provision of electrically controlled means for operating the control dials of the set which is so constructed and arranged as to instantly start and stop said dials to afford accurate tuning, and which is easily and conveniently manipulated.

A still further object is to provide a remote 20 control apparatus for radio receiving sets which is simple, compact and inexpensive in construction, which can be readily applied to and installed in existing radio sets without materially altering their construction and which is positive and efficient in operation.

Other objects of the invention consist in certain novel features of construction and arrangement of parts hereinafter described and particularly pointed out in the appended claims.

30 In the accompanying drawings:—

Figure 1 is a front elevation of a radio receiving set equipped with my improvement and showing the control unit, which is located at a remote point from the set, in perspective. Figure 2 is a front face view of the mechanism disposed within the set and operatively connected to the parts thereof, such as the tuning dial and volume control, which are subject to control. Figure 3 is a transverse vertical section taken in the plane 35 of line 3—3, Figure 1. Figure 4 is a top plan view of the operative mechanism shown in Figure 2. Figure 5 is an enlarged longitudinal section taken on line 5—5, Figure 4. Figure 6 is a transverse section taken on line 6—6, Figure 4. Figure 7 is a diagrammatic view of the electric circuits 40 between the radio set and the control board. Figure 8 is a diagrammatic view of the magnetic clutch for controlling the tuning of the set. Figure 9 is a similar view of the solenoid for governing the volume control. Figure 10 is a transverse section on line 10—10, Figure 4. Figure 11 is a fragmentary cross section taken on line 11—11, Figure 10.

Similar characters of reference indicate corresponding parts throughout the several views.

In its general organization, my improved remote control apparatus comprises a motion transmitting mechanism disposed conveniently within the radio set and operatively connected to the customary adjusting elements of the set, such as the tuning dial and the volume control element, and a selective controlling device which may be disposed at a remote point from the radio set, either in the same room or from any other place or room where the radio set may be heard or wherein a loud speaker is located, and which automatically governs the selection of the station and the tone volume of the reception.

By way of example, I have shown my invention in connection with a cabinet type of radio receiving set 10 having the usual manually-controlled switch knob 11 for governing the current supply to the set, the station selecting knob 12 which controls the revolving tuning dial 13 having meter or kilocycle graduations thereon, and a volume control knob 14.

The motion-transmitting mechanism which is housed within the radio cabinet for actuating the dial 13 and the volume control device of the set is preferably constructed as follows:—

The operative parts of this mechanism are mounted as a practically complete unit in a suitable frame 15 rising from a platform 16 and disposed at a convenient place within the cabinet, or connected direct to the radio chassis as desired. Attached to this frame is an electric induction motor 17 whose shaft 18 has a worm 19 thereon meshing with a worm wheel 20 applied to a transverse driving shaft 21 journaled at its ends in appropriate bearings secured to the end walls of the frame. Disposed parallel to this driving shaft is a driven shaft 22 on which revolvable electromagnetic drums 23, 24 are loosely mounted having corresponding ring gears 25, 26 thereon. These drums are driven in opposite directions about their supporting shaft, the drum 23 having its gears 25 in constant mesh with a pinion 27 fixed on the shaft 21 for revolving the same in one direction, while the drum 24 is driven in the reverse direction by a pinion 28 meshing with its gear and mounted on a counter shaft 29 driven from the shaft 21 by intermeshing gears 30 and 31. The drum-shaft 22 is operatively connected to the tuning dial 13 to control its turning in either direction during the station-selecting operation and for this purpose it may be directly connected to the dial or condenser shaft should the relative position of the parts permit it, or as shown in the drawings, said drum-shaft may have

a sprocket wheel 32 fixed on one end thereof and connected by a sprocket chain 33 with a similar sprocket wheel 34 applied to the spindle 35 of the station-selecting knob 12 of the radio set. This spindle has a gear or similar device 36 thereon meshing with a gear 37 secured to the shaft 38 of the tuning dial 13. Thus as the drum-shaft is caused to turn in one direction or the other, the tuning dial is turned in a corresponding direction.

10 The control of the drum-shaft 22 to turn it in one direction or the other is preferably effected thru the medium of a magnetic clutch, wherein the drums 23, 24 constitute the revolving elements of the clutch and a flexible steel disk or armature 39 constitutes the movable or shiftable element of the clutch. This disk is fixed on the shaft 22 and is disposed centrally between the opposing edges of the electromagnetic drums, the disk being so constructed as to be capable of flexing axially and attracted toward and into positive gripping engagement with one or the other of the drums to accordingly govern the direction of movement of the drum-shaft and thence the tuning dial 13. The drums 23, 24 contain appropriate coils or windings 40, 41, respectively, and are included in a control circuit, so that when the coil of the drum 23 is energized the clutch-disk 39 is attracted to it and the drum-shaft is driven simultaneously in the same direction. When the coil of the companion drum 24 is energized, the clutch-disk is attracted to it and the drum-shaft is accordingly driven in the reverse direction. By this construction and arrangement of parts, the tuning dial is automatically turned in either direction just as though one were manipulating the control knob 12, the gear ratio of the transmitting mechanism being such that the dial is turned at a comparatively slow speed.

15 The mechanism for operating the volume control device of the set, which device may be in the form of a potentiometer 42 including a revolving wiper or contact arm 43, is likewise driven from the electric induction motor 17 and to this end the driving gear 30 meshes with a gear 44 fixed 20 on a longitudinally shiftable shaft 45 disposed parallel to the driving shaft 21 and surmounting the drums 23, 24 at one side thereof, as seen in Figures 4 and 5. Said shaft 45 is provided with spaced friction disks 46, 47 or like drive elements, one or the other of which is adapted to frictionally engage a similar disk 48 fixed on a shaft 49 disposed at right angles to the shaft 45 and having a worm 50 thereon engaging a worm wheel 51 fixed on an upright shaft 52 which carries the 25 volume control contact arm 43 at its upper end, as shown in Figure 6. The shifting of the friction disk shaft 45, to effect a rotation of the volume control arm in one direction or the other and thus govern the tone volume of the reception, may be accomplished in any appropriate manner but 30 preferably through the medium of a solenoid 53 having two coils or windings 54, 55 and whose movable iron core or plunger 56 may be formed as an extension of the shaft 45, as seen in Figure 5. 35 The solenoid is included in a control circuit, so that when its coil 54 is energized one of the drive disks 46, 47 is brought from a normal neutral position into driving engagement with the disk 48 to actuate the volume control to increase the volume of the reception, while when the companion coil 55 is energized the corresponding disk is actuated to reverse the direction of motion of the parts and decrease the volume of the reception.

40 Inasmuch as the gears 30 and 44 must be in mesh at all times and the gear 44 moves length-

wise with its shaft 45 relative to the companion gear 30 during the shifting movements of the shaft to govern the volume control device, these gears are of sufficient width to remain in proper engagement.

45 If desired, the mechanism for operating the volume control may be substantially identical in construction with that employed for actuating the tuning dial.

50 The selective controlling mechanism, for governing the motion-transmitting mechanisms heretofore described at a point remote from the radio receiving set, is preferably housed within a portable cabinet 57 and includes electrical devices for governing, at the will of the user, the adjustable devices of the set, as well as the motor 17. The latter is controlled by a switch 58 which may be disposed centrally of the cabinet, as seen in Figure 1, while the coils 40, 41 of the companion magnetic clutch elements 23, 24 for 55 governing the turning movements of the tuning dial 13 are controlled by corresponding switch buttons 59, 60 and the solenoid 53 for governing the volume control 42 is controlled by switch buttons 61, 62. Also mounted on the control 60 cabinet are indicators 63, 64, the former for indicating the corresponding movements of the tuning dial 13 in the radio set and having like kilocycle graduations thereon, and being so connected with the transmitting mechanism as to 65 be simultaneously movable with such dial and register corresponding meter or kilocycle readings, and the indicator 64 responding to and registering with the movements of the volume control 42 in the set. Operatively connected with 70 the clutch shaft 22 to turn therewith in one direction or the other is a shaft 65 having a gear wheel 66 thereon meshing with a pinion 67 on said shaft 22. Axially disposed about the shaft 65 and fixed to a bracket 68 supported from 75 the frame 15 is a rheostat or like controlling device 69 over which a wiper or contact arm 69a fixed on said shaft is adapted to travel. This rheostat is electrically connected to the dial indicator 63 of the control cabinet to effect a corresponding movement of its pointer and register the companion readings of the tuning dial 13. In the same manner, the volume control 42, which is actuated by the solenoid 53 and associated parts, is electrically connected to the volume indicator 64 of the control cabinet.

80 The control circuits for the various elements just described are shown in Figures 7, 8, and 9, and are as follows:

85 The source of current supply for operating the motor 17 and the circuit of the radio receiving set may be derived from a domestic 110 volt line, the frame 15 having a socket 70 for receiving such a plugged connection and a socket 71 for connecting such line current to the set. The circuit of the motor 17 for operating the motion-transmitting mechanism of the apparatus includes the wires 72, 73 leading from the socket 70 to corresponding terminal posts 74, 75 mounted on a panel 76 adjoining the frame 15, and the wires 77, 78 leading from such posts to the switch 80 on the control cabinet. The line current from the socket 70 is also connected to the socket 71, into which the set is plugged, by wires 79, 80, and a switch 81 is interposed in this circuit to close and open it and thereby accordingly start the radio set or shut it off, just as does the manual switch knob 11 of the set. Also included in the circuit of this radio control switch 81 is a tell-tale lamp or indicator 82 mounted on the 85

control board and connected by a wire 82^a with the terminal wire 78 of the motor switch 58 and by a wire 83 with a terminal post 84 mounted on the panel 76 and connected by a wire 85 with 5 the circuit including the radio control switch 81. When the latter is closed, the circuit is closed thru the lamp 82, indicating to the party manipulating the remote control board that the set has been switched "on" and is ready for reception 10 upon the proper actuation of the tuning and volume control devices.

The control switch 81 is preferably mounted on the frame 15 adjacent to the gear wheel 66, which transmits motion from the clutch shaft 22 15 to the revolving contact arm 69^a of the rheostat 69 and accordingly governs the corresponding movement of the pointer on the tuning indicator 63 of the control cabinet. This switch is automatically shifted at predetermined points to its "on" 20 and "off" positions by a trip pin 86 applied to said gear which, the actuating lever 87 of the switch being disposed in the path of travel of the trip pin, is shown in Figure 10.

The coils 40, 41 of the clutch drums 23, 24, 25 which control the turning of the tuning dial 13 in one direction or the other, are included in a circuit including the switch buttons 59, 60 on the control cabinet. One terminal of each switch button is joined to a common feed wire 88 connected with a source of current supply 89, while the companion terminals are joined by wires 90, 91 with corresponding binding posts 92, 93 on the panel 76, which in turn are connected by wires 94, 95 with the respective coils 40, 41, the 30 other ends of such coils being grounded. Interposed in these coil circuits and automatically actuated at a predetermined point during the revolution of the gear wheel 66 are limit switches 96, 97 which act to break such circuits and prevent the tuning dial of the radio set and its 35 indicator dial 63 on the control cabinet rotating beyond the extreme readings of such parts. To this end, the limit switch 96 may be disposed in lateral alinement with the control switch 81 and be actuated simultaneously therewith by the trip pin 86 on the gear wheel 66, the lever 87 of 40 said switch 81 being connected by a tie bar 98 with the lever 99 of the limit switch for this purpose. Thus, when the tuning dial 13 of the 45 set and the companion indicator pointer reach a predetermined position at the left or high reading side of the dial 63, the pin 86 will trip both switches 81, 96 to their "off" position and not only break the circuit of the radio set, but the 50 circuit of the corresponding clutch coil 40. The other limit switch 97 functions in a similar manner and has its lever 100 disposed in the path of a trip pin 101, likewise applied to the gear wheel 66, so that when the tuning dial and its indicator 55 pointer reach a predetermined position at the right or low reading side of the dial 63, this switch will be tripped to its "off" position and the corresponding clutch coil 41 deenergized and the clutch released, thereby automatically arresting the rotation of the affected parts. It will 60 therefore be understood that when one of the limit switches 96, 97 has been cut "off" to break the circuit it governs, the other one is "on", so that when the corresponding switch button 59 65 or 60 is depressed or closed, its circuit including the companion clutch coil will be closed and the tuning dial 13 associated parts can be accordingly actuated and the set be operative. However, when the limit switch 96 and the radio set controlling switch 81 are opened by rea-

son of the tuning dial and the indicator 63 reaching the limit of their movement at the lower meter or high kilocycle side of the dial, that is to the left or in a counter-clockwise direction, then the set is cut "off" as well as the circuit of the clutch coil 40. At this time the switch 97 is closed and when the companion switch button 60 is depressed, the circuit of the clutch-coil 41 is closed and motion is transmitted to the parts to turn the dial and indicator 10 to the right or in a clockwise direction from the high kilocycle reading to the low. The trip pins 86, 101 are so disposed relatively to the switches 81, 96 and 97, that they function not only to open the switches at the extreme limits of movement of the tuning dial 13 and corresponding indicator 63, but they also act to again close said switches at predetermined points so that the circuits including the control switch buttons 59 15 will be in readiness to govern the associated parts 20 for tuning purposes. During the intermediate positions of the tuning dial and its indicator, the switches 81, 96 and 97 are all closed and their circuits are accordingly made or broken to regulate the tuning by depressing one or the other 25 of the control buttons 59, 60.

The circuit including the tuning rheostat 69 and the dial indicator 63 which is responsive thereto in accordance with the turning of the tuning dial 13, consists of a feed wire 102 connected at one end to a source of current supply 30 and at its opposite end to the rheostat coil, the other end of the latter being grounded; a wire 103 connecting the center tap or contact arm 69^a of this rheostat with a binding post 104 on 35 the panel 76 and thence by a wire 105 to one terminal of the dial indicator, the other terminal of the latter being connected by a wire 106 to a variable resistance 106^a, said resistance is for the purpose of adjusting the pointer of the indicator 63; to conform with the kilocycle graduations on the tuning dial 13, thence to a ground tap 107 on said panel. Thus, as the rheostat arm 69^a is turned in one direction or the other in response to the tuning of the set from the control cabinet by the closing of the switch buttons 59, 60 which govern the clutch mechanism 23, 24, 39, the pointer on the dial indicator 63 is correspondingly moved to visually indicate to the operator the same kilocycle reading which exists on the tuning dial 13 within the set. 40

The coils 54, 55 of the volume control solenoid 53, which governs the rotation of the contact arm 43 of the volume control 42 to increase or decrease the tone volume of the receiving set, are 45 included in the circuit of the switch buttons 61, 62 on the control cabinet 57. One terminal of each switch button is joined to the common feed wire 88, while the companion terminals are joined by wires 108, 109 with corresponding binding 50 posts 110, 111 on the panel 76, which in are connected by wires 112, 113 with the respective solenoid coils 54, 55, the other ends of such coils being grounded. Thus, when either of the switch buttons 61, 62 is closed, the solenoid is accordingly energized to shift the drive means associated therewith for rotating the volume control arm 43 in a corresponding direction to regulate and control the volume of the reception. 65

The circuit including the volume control 42 and its companion dial indicator 64, which is responsive thereto, consists of a feed wire 114 connected at one end to a source of current supply and its opposite end to the resistance coil, the other end of the latter being connected by a wire 115 to a 70 75

- ground tap 116 on the panel 76; a wire 117 connecting the center tap or contact arm 43 of the volume control with a binding post 118 on said panel and thence by a wire 119 to one terminal 5 of the dial indicator 64, the other terminal of the latter being connected by a wire 120 with the ground tap 116. Thus, as the volume control arm 43 is turned in one direction or the other in response to the motion transmitted to it through 10 the volume control transmitting mechanism actuated by the solenoid 53, the pointer on the dial 64 is correspondingly moved to visually indicate to the operator the same volume setting as is registered in the set.
- 15 In the drawings, the various electrical connections between the control mechanism within the radio set and those within the control cabinet 57 are shown embodied in a flexible cable 121 having suitable plugs 122 at its ends for coupling it to the respective parts.
- If desired, instead of employing the switch buttons 61, 62 and associated parts for regulating the volume control, said volume control may be mounted in control cabinet 57, operated by actuating knob 123, as shown in Figure 1, and electrically connected to the radio receiving set.
- The operation of the remote control apparatus is as follows:—
- Assume that the adjustable or control parts of 30 the radio have all been shut off, that is with the switch 97 closed and the tuning and volume control knobs at their extreme left hand positions and that the pointers of the indicator dials 63, 64 are in like positions and that the switch 58 is 35 "off". Under these conditions the magnetic clutch 23, 24, 39 of the driving mechanism for controlling the remote tuning of the set is in neutral position and the solenoid 53 for regulating the volume control is in a like position, while 40 the switches 81 and 96 are "off" and the switch 97 is "on". Also assume that the set is properly connected with the source of current supply required and that the cable 122 of the control cabinet is plugged into the set.
- 45 In starting the apparatus, the switch 58 is snapped "on" to operate the motor 17, the mechanisms which it controls being in neutral with the drums 23, 24 of the magnetic clutch idly rotating in opposite directions and the clutch-disk 50 59 disposed between them, while the friction disks 46, 47 governed by the volume control solenoid 53 also idly rotate and are disengaged from the driven disk 48. Next, the switch button 60 is depressed to close the circuit of the clutch-coil 55 41, the limit switch 97 in said circuit having been previously closed, which attracts the clutch disk 39 to the revolving coil-drum 23, thereby transmitting motion to the shaft 22 and thence to the tuning dial 13 and rheostat-arm 69^a, the latter being connected to the indicator dial to register the position of the tuning dial and the parts moving in a clockwise direction. During the initial movement of the drum-shaft 22, the trip pin 86 on the revolving gear 66 encounters the tie 60 65 bar 93 of the joint switches 81, 96 and closes them, thereby turning the radio set "on" and placing the circuit including the switch 96 in readiness to be closed whenever the companion switch button 59 on the control cabinet is depressed to 70 thereby effect the rotation of the parts under control in the reverse or counter clockwise direction. The moment the switch 81 is automatically closed, the circuit of the lamp 82 is likewise closed and the same lighted, indicating to the operator 75 that the set is "on" and ready to function. The operator continues to hold the switch button 60 in its depressed circuit-closing position, until the indicator 63 before him indicates the station desired to be heard, at which time such button is released, the corresponding clutch circuit is immediately opened and the tuning dial and its companion indicator is "instantly" stopped. In the event that the setting of the tuning dial is beyond that desired, then the switch button 59 is depressed, which closes the circuit of the companion clutch-coil 40 and rotates the control parts in the reverse direction, the button being released when the desired setting is reached.
- The volume control is effected by depressing one or the other of the switch buttons 61, 62, 15 which, as heretofore described, govern the circuit of the solenoid 53 and control the shifting of the disks 46, 47 into and out of engagement with the disk 48 which transmits motion to the arm 43 of the volume control 42, the closing of the switch 20 button 61 resulting in an increase in tone volume and the closing of the button 62 resulting in a decrease in tone volume and the indication of such volume being recorded at the indicator 64 on the control cabinet 57.
- If, during the tuning operation, the dial 13 and corresponding indicator 63 travel beyond their extreme readings to the right or to the left, respectively, the trip pin 101 will encounter the switch 97 and trip it to "off" position which will 30 release the clutch and "instantly" and automatically arrest further rotation of those parts, or the trip pin 86 will encounter the switches 81, 96 and trip them to "off" position to release the clutch and also cut off the current to the radio 35 set as well as putting out the tell-tale lamp 82 on the control cabinet. In this last-named position of the parts, the radio set is shut off and if it is desired to then discontinue operations completely, the switch 58 is snapped "off" to stop 40 the motor 17.
- I claim as my invention:—
1. A remote control apparatus for radio receiving sets having an adjustable element, comprising a driven member operatively connected to 45 said adjustable element to turn it in one direction or the other, a driving means consisting of oppositely rotating drums disposed axially of the driven member to revolve independently thereof and having electro-magnets carried thereby, said drums being spaced apart axially, a magnetic clutching element common to said electro-magnets fixed on said driven member in the space between said drums for selective engagement with one or the other thereof, and a portable control 50 device including devices connected with the electro-magnets of said drums for actuating the clutching element to one or the other of its operative positions to govern the rotation of said 55 adjustable element in one direction or the other.
2. A remote control apparatus for radio receiving sets having a part to be actuated comprising a driving means including oppositely rotating electro-magnets disposed in spaced axial 60 relation, a driven transmission means operatively connected to said actuatable part and including a shaft disposed axially of said rotating electro-magnets and carrying a shiftable member constituting an armature disposed axially between and common to said electro-magnets, electric circuits for the latter, and a portable control device having switches included in the circuits of said electro-magnets.
3. A remote control apparatus for radio re- 75

ceiving sets having a part to be actuated, comprising a driving means including oppositely rotating electro-magnets disposed in axially spaced relation, means for rotating the same, a driven transmission means operatively connected to said actuatable part and including a shiftable member constituting an armature disposed axially between and common to said electro-magnets, electric circuits for the latter, a portable control device having switches included in the circuits of said electro-magnets, and an indicator applied to said device and operatively connected to said driven transmission means for indicating the corresponding movements thereof.

5 4. A remote control apparatus for electrically operated instruments having a control switch and a part to be actuated, comprising a driving means including axially-aligned oppositely rotating electro-magnets, a driven transmission means operatively connected to said actuatable part and including a shiftable member constituting an armature disposed between and common to said electro-magnets, means governed by said transmission means for automatically controlling the opening and closing of said control switch, electric circuits for the electro-magnets, and a control device having switches included in the circuits of said electro-magnets, one of said switches being actuated by said control switch governing means for simultaneously opening or closing the same therewith.

10 5. A remote control apparatus for electrically operated instruments having a control switch and a part to be actuated, comprising a driving means including oppositely rotating electro-magnets, a driven transmission means operatively connected to said actuatable part and including a shiftable member constituting an armature disposed axially between and common to said electro-magnets, means governed by said transmission means for automatically controlling the opening and closing of said control switch, electric circuits for the electro-magnets, a control device having switches included in the circuits of said electro-magnets for automatically breaking such circuits and limiting the movement in one direction of the part to be actuated, one of said switches being actuated by said control switch governing means for simultaneously opening or closing the same therewith, and means governed by said transmission means for automatically controlling the opening and closing of the other electro-magnet governing switch.

15 6. A remote control apparatus for radio receiving sets having a part to be actuated comprising a driving means including oppositely rotating electro-magnets, a driven transmission means operatively connected to said actuatable part and including a shiftable member constituting an armature disposed axially between and common to said electro-magnets, electric circuits for the latter, switches included in said circuits, a member revolvable with said transmission means and having trip elements thereon engage-

able with said switches for automatically shifting them to their "on" and "off" positions at predetermined points in the rotation of said member, and a remote control device having manually-actuated switches included in the circuits of said electro-magnets for controlling said transmission means at will.

7. A remote control apparatus for radio receiving sets having a part to be actuated, comprising a driving means including oppositely rotating electro-magnets, a driven transmission means operatively connected to said actuatable part and including a shiftable member constituting an armature disposed axially between and common to said electro-magnets, electric circuits for the latter, an electric control element actuated by and responsive to the movements of said transmission means, a remote control device having switches included in the circuits of said electro-magnets for governing the transmission means to actuate said part in one direction or the other, and an indicator applied to said device and operatively connected to said control element for indicating the corresponding movements of said transmission means and the part actuated thereby.

10 8. In a remote control apparatus for a radio receiving set having a movable element for tuning the set to desired wave lengths, forward and reverse driving means including revolving axially-aligned electro-magnets, a driven transmission means operatively connected to the tuning element and including a shiftable armature disposed axially between and common to said electro-magnets, electric circuits including the latter, a control switch for operating the radio set, means governed by said transmission means for opening and closing the control switch at predetermined points in its movement, a remote control device having switches included in the circuit of said electro-magnets, an indicator operatively connected to the transmission means of the tuning element for indicating its corresponding movements and wave settings, and a pilot lamp included in the circuit of said radio control switch.

15 9. A remote control apparatus for radio receiving sets having an adjustable element, comprising a drive shaft, a driven transmission means operatively connected with said adjustable element, a solenoid including two coils and a revolving plunger geared to said drive shaft, means for coupling said plunger with said transmission means to rotate the same in one direction or the other, electric circuits including the solenoid-coils, and a remote control device for governing said coupling means consisting of switches included in the circuits of said solenoid-coils, whereby one or the other of the latter is energized to shift the solenoid plunger into driving engagement with said transmission means to operate the adjustable element in one direction or the other.

HENRY Y. HENNING.
